CLUTCH

Heinrich Wörner, Bischofsheim, Germany, assignor, by direct and mesne assignments, to Fichtel & Sachs A. G., Schweinfurt-on-the-Main, Germany, and Mecano G. m. b. H., Frankfort-on-the-Main, Germany

Application April 7, 1930, Serial No. 442,341,
and in Germany November 9, 1929

2 Claims. (Cl. 192—110)

Disc couplings, e. g. for power driven vehicles, in which the pressure ring is pressed against the coupling disc by means of two-armed pressure levers, often have the disadvantage that a uniform pressure is not exerted on all parts of the pressure ring. This is due to the fact that all the pressure levers are actuated by a sleeve and the unavoidable defects in manufacture and arrangement prevent the application of the pressure levers with equal pressures. The result is that the useful friction between the coupling disc and pressure ring or flywheel disc does not reach its highest value, and that, moreover, a non-uniform wearing of the above mentioned parts occurs.

15 The object of the present invention is to equalize the pressures exerted on the pressure levers by the arrangement of a movable abutment for the pressure levers, so that the disadvantages described above are avoided. The abutment at the same time serves to make it possible to adjust the pressure levers against the coupling discs according to their wear.

20 The accompanying drawing illustrates a constructional form of the invention by means of a cross section in the vertical plane of symmetry of a two-disc coupling for power driven vehicles.

25 Between the flywheel disc 1 of the driving motor and the two pressure rings 2, coupling discs 3 are arranged in a known manner, which are mounted on the shaft 4 to be coupled. The pressure required for coupling is exerted by means of a number of pressure levers 5, which are mounted on the coupling housing 6 and are actuated by a common sleeve 7, upon which a spring 8 presses. By displacing the sleeve 7 towards the housing 6 the coupling may be disengaged in known manner.

30 According to the present invention the pressure levers 5 are not mounted directly on the housing 6, as has hitherto been customary, but they rest by means of bearing pins 9 in sockets

10 which are formed in the pressure equalizing ring 11. The inner surface of the same is spherical and fits on the convex spherical outer surface of a ring 12 which is provided on the projecting nose 13 of the housing, and may be screwed 60 backwards and forwards by means of a screw-thread.

35 In engaging the coupling the sleeve 7 moves outwards under the pressure of the springs 8 and thereby pulls the longer limbs of the pressure levers 5, so that the pressure levers press on the outer pressure ring 2 with their shorter limbs. A load is thrown on the pressure equalizing ring 11 by the reaction on the bearings of the pressure levers 5, which ring is displaced on the bearing surface of the ring 12 until the load is uniformly distributed amongst the pressure levers 5. As the coupling discs 3 are progressively worn away, a gradual alteration of the initial position 75 of the pressure levers 5 takes place. In order to compensate for this alteration, the ring 12 is screwed in towards the housing 6 until the pressure levers 5 again take up their original initial positions.

40 What I claim is:

1. A pressure equalizing device for clutches comprising a clutch casing, a cover plate therefor, pressure levers arranged in the casing, a pressure equalizing ring arranged exteriorly of the cover plate, bearing pins slidably mounted through the cover plate and to which the pressure levers are pivoted, sockets on the pressure equalizing ring in which the bearing pins rest, and a ring carried by the outer surface of the cover plate and provided with a spherical surface, over which surface the pressure equalizing ring is movable.

45 2. A pressure equalizing device as claimed in claim 1 in which the ring with a spherical surface is screwed on to the cover plate so as to be 95 adjustable.

HEINRICH WÖRNER.
